LINER HANGER

Elwin B. Hall and Arthur L. Armentrout, Los Angeles, Calif., assignors of one-third to Virgil P. Baker, Los Angeles, Calif.

Application January 16, 1939, Serial No. 251,071

13 Claims. (Cl. 166—1)

This invention relates to well tools and relates more particularly to liner hangers for supporting liners in wells. A general object of this invention is to provide a simple, dependable and readily manipulated liner hanger.

In conditioning an oil well for production it is the usual practice to install a tubular perforate liner in the producing portion of the well. It is a common practice to employ a liner hanger to support the liner in the selected position. A typical liner hanger is usually rigidly fixed to the liner and embodies slips for gripping the well casing to support the liner. The slips of a conventional liner hanger are held in a retracted condition by a latch means so that the equipment may be readily lowered into the well and the latch means is usually released by a turning movement when the liner is in the correct or selected position. In many cases the portion 20 of the well in which the liner is installed is crooked or inclined to such an extent that the liner binds on the wall of the well and cannot be turned. Under such conditions it is difficult and sometimes impossible to release the latch 25 means of the hanger to condition the slips for operation.

Another object of this invention is to provide a liner hanger that may be easily and quickly operated and set with the liner free and turnable 30 or with the liner held against turning by reason of the inclination or contour of the well.

Another object of this invention is to provide a liner hanger that requires only simple manipulations of the setting string to effect its operation.

Another object of this invention is to provide a liner hanger embodying a novel bearing means for permitting turning of the hanger relative to the liner to release the latch means of the slips 40 and a novel releasable means initially holding the hanger and liner against relative turning so that the slips cannot be unintentionally or prematurely actuated while lowering and positioning the liner.

Another object of this invention is to provide a liner hanger of the character referred to in which the releasable means for initially preventing relative turning between the liner and hanger is released by a go-devil or weight dropped 50 through the setting string, said weight being recovered from the well when the setting string is withdrawn following the actuation of the hanger.

A further object of this invention is to provide a liner hanger of the character referred to

that is adapted to be installed at the lower end of the liner to support the liner from its lower end.

The various objects and features of our invention will be fully understood from the following detailed description of typical preferred forms and applications of the invention, throughout which description reference is made to the accompanying drawings, in which:

Fig. 1 is a side elevation of one form of the 10 invention in the normal or unactuated condition and associated with a typical liner and setting string in a typical well. Fig. 2 is an enlarged fragmentary longitudinal detailed sectional view of the principal parts of the device illustrated 15 in Fig. 1 showing the parts in the normal or unactuated positions. Fig. 3 is a view similar to Fig. 2 illustrating the positions of the parts following the setting or actuation of the hanger. Fig. 4 is an enlarged fragmentary longitudinal 20 detailed sectional view illustrating the rotatable connection and the associated releasable holding means with the parts in the initial positions. Fig. 5 is an enlarged transverse detailed sectional 25 view taken as indicated by line 5—5 on Fig. 2. Fig. 6 is an enlarged transverse detailed sectional view taken as indicated by line 6—6 on Fig. 3. Fig. 7 is an enlarged transverse detailed sectional view taken as indicated by line 7—7 on Fig. 2. Fig. 8 is an enlarged transverse detailed sectional view taken as indicated by line 8—8 on Fig. 3. Fig. 9 is a fragmentary longitudinal detailed sectional view of the upper portion of another embodiment of the invention 30 illustrating the hanger attached to the lower end of the liner and showing the setting string in elevation. Fig. 10 is a view similar to Fig. 9 showing the lower portion of the tool illustrated in Fig. 9 with certain parts in elevation, and Fig. 11 is a view similar to Fig. 10 showing the 40 liner hanger set or actuated.

The tool of the invention illustrated in Figs. 1 to 8, inclusive, of the drawings is applied to the upper end of a typical well line L and is employed to suspend the liner from the well casing 45 C. The apparatus of the invention illustrated in Figs. 1 to 8, inclusive, may be said to comprise, generally, the liner L, a hanger H conditioned or released for operation by turning movement, a rotatable connection 48 between the liner L and 50 the hanger H allowing turning of the hanger relative to the liner L to condition the hanger for actuation and releasable means 44 for holding the liner L and the hanger H against relative turning.

The liner L is an elongate, tubular member or assembly adapted to be arranged in the well to extend from the lower end of the casing C into the open producing portion of the well. The liner L may be of any required length and may embody a number of connected sections in accordance with the usual practice. In the drawings we have shown only the upper portion of the liner L extending through the casing C. In the particular construction illustrated a short tubular section 12 is provided on the upper end of the liner L and is connected with the liner proper by a threaded coupling 13.

The hanger H is adapted to grip the interior of the casing C to support or suspend the liner L in the selected position. In the form of the invention being described the hanger H is associated with the upper end of the liner L. The hanger H includes an elongate tubular body 14 arranged in co-axial relation with the liner L. A suitable setting tool adapter 15 is threadedly connected with the upper end of the hanger body 14 to facilitate the installation of the hanger and liner L. T or J slots 16 are provided in the wall of the adapter 15 and enter the adapter from its upper end. The inner or lower arms of the slots 16 terminate in upwardly and downwardly extending branches 17. A mandrel 18 is adapted to enter the adapter 15 and has lugs 19 for cooperating with the slots 16 and their branches 17. The setting tool mandrel 18 is secured to the lower end of a tubular setting string 20 for lowering the liner L and the hanger H into the well.

The hanger H further includes slip means for gripping the interior of the casing C. This slip means includes a cone 21 surrounding the body 14 below the adapter 15. The cone may be shiftable on the body 14. A pin 22 on the body 14 may extend into a vertical slot 23 in the cone 21 to hold the cone against turning relative to the body and to limit the vertical shifting of the cone. A packing ring assembly 24 may be provided on the body 14 between the lower end of the adapter 15 and the upper end of the cone 21. The packing ring assembly 24 is expanded into sealing engagement with the casing C when the weight of the liner L is transmitted through it from the adapter 15 to the cone 21. A set of slips 25 is engaged about the cone 21. The slips 25 have shiftable dove-tailed connections 26 with the cone 21 to be held against displacement and turning movement with respect to the cone and body 14. The outer sides of the slips 25 are toothed to effectively grip the inner wall of the well casing C.

A releasable latch means is provided to control the slips 25. The latch means for the slips 25 includes a ring 27 freely shiftable on the section 12 of the liner L. Spring reins 28 are secured to the lower ends of the slips 25 and extend downwardly to the ring 27. The reins 28 are attached to the ring 27 so that the several slips 25 are connected with the ring. Downwardly projecting latches 29 on the ring 27 releasably cooperate with the pins 30 projecting from the liner section 12. The latches 29 are hook-like elements releasably engageable with the pins 30 to hold the slips 25 in their down or retracted positions illustrated in Figs. 1 and 2 of the drawings. The latches 29 may be freed from the pins 30 by a turning movement followed by a vertical movement. The reins have outwardly bent or curved portions 31 below the ring 27. The rein portions 31 frictionally engage against the inner wall of the casing C to resist downward movement of the

slips 25. The slip reins 28 may pass through vertical grooves 32 in the exterior of the hanger body 14. The engagement of the reins 28 in the grooves 32 assists in preventing turning movement of the slips 25 and aids in supporting the reins 28 against turning forces.

The swivel connection or rotatable connection 10 secures the hanger H to the upper end of the liner L in such a manner that the hanger H may be turned relative to the liner L to release the latches 29 from the pins 30 to condition the slips 15 for actuation. The rotatable connection 10 is preferably in the nature of an anti-friction bearing connection. In the form of the invention being described the connection 10 includes a sub or tubular member 33 threadedly connected with the upper end of the liner section 12 and extending into a socket 34 in the lower end of the hanger body 14. The wall of the socket 34 and the exterior of the member 33 have registering ball races 35 and a series of balls 36 is arranged in the races 35 to rotatably connect the hanger H with the liner L. The balls 36 may be inserted in the races 35 through a radial opening 37 in the hanger body 14. A plug 38 normally closes the opening 37. It will be apparent how the balls 36 arranged in the races 35 connect the liner L and the hanger H against longitudinal movement and separation and allow free relative turning between the hanger and liner.

The releasable means 11 serves to connect the liner L and the hanger H against relative turning so that the equipment may be run into the well without danger of prematurely releasing and setting the slips S. The means 11 includes or provides sets or pairs of registering openings 39 and 40 in the walls of the overlapping or telescoping portions of the member 33 and the hanger body 14, respectively. In practice the openings 40 may be in the nature of notches in the lower end of the body 14. The lower walls of the openings 39 preferably slope downwardly and inwardly as best illustrated in Figs. 2 and 4 of the drawings. The means 11 further includes shiftable pins or blocks 41 in the sets of registering openings 39 and 40. The blocks 41 may be sufficiently long to extend completely through the sets of openings 39 and 40 and to project from the inner wall of the member 33. The outer portions of the blocks 41 are preferably longitudinally curved so that the blocks may be drawn downwardly and inwardly from the openings 40. Pins 42 are arranged in openings 43 in the member 33 and pass through transverse curved slots 44 in the blocks 41 to prevent loss or detachment of the blocks from the member 33. Fingers 45 of reduced thickness may be provided on the outer ends of the blocks 41 to extend into slots 46 in the adjacent slip reins 28. The engagement of the fingers 45 in the slots 46 positively locks the slips 25 in their retracted positions.

The shiftable lock blocks 41 are connected by a link 47. The link 47 may be in the nature of a leaf spring riveted or otherwise secured in notches 48 in the inner ends of the blocks 41. The spring link 47 is normally straight and serves to hold the blocks 41 in their outermost positions where they extend through the registering openings 39 and 40. It will be seen that the blocks 41 engaged in the openings 39 and 40 prevent relative turning between the hanger body 14 and the liner L.

The releasable means 11 is adapted to be released by a go-devil or weight element 50 dropped through the tubular setting string 20. The ele-

ment 50 is proportioned to readily pass downwardly through the string 20 and through the hanger body 14. The lower end of the element 50 is adapted to engage the link 47 or the inner parts of the blocks 41 to draw the blocks downwardly and inwardly to positions such as illustrated in Fig. 3 of the drawings where they are clear of the openings 40 in the hanger body 14. A head 51 is provided on the upper end of the weight element 50 to assist in guiding the element through the string S. The adapter 18 is preferably provided with an internal upwardly facing shoulder 52, adapted to be engaged by the lower end of the head 51. In the event that the weight element 50 strikes the blocks 41 with sufficient force to break the link 47 the head 51 may come into engagement with the shoulder 52 to limit the downward travel of the element 50. The shoulder 52 is adapted to engage the head 51 to lift and support the element 50 so that the element is removed from the well upon withdrawal of the setting string 20. It is preferred to provide a central longitudinal passage 53 in the weight element 50 to permit the free flow of fluid through the element.

The invention may include means for resisting turning of the liner L to facilitate the release and actuation of the slips 25 when the condition of the well is such that the liner is otherwise free for turning movement. This means may be in the form of a tail piece secured to the upper section 12 of the liner. As illustrated in the drawings vertically spaced rings 54 may be welded or otherwise fixed to the liner section L and outwardly bowed leaf springs 55 may extend between the rings 54. The springs 55 are adapted to frictionally bear against the inner wall of the casing C to resist turning of the liner L.

In the use and operation of the form of the invention illustrated in Figs. 1 to 8 of the drawings the liner L is made up and the hanger H is connected with its upper end. The rotatable connection 10 is employed to connect the hanger H with the liner L. The mandrel 18 on the lower end of the string 20 is inserted in the adapter 15 and its lugs 19 are engaged in the vertical slot branches 17 so that the assembly of the hanger H and the liner L may be lowered into the well on the string 20. When the liner L has reached the selected position in the well the go-devil or weight element 50 is dropped through the string 20. The lower end of the element 50 strikes the link 47 or the blocks 41 to draw the blocks downwardly and inwardly to positions such as illustrated in Fig. 3 of the drawings. The engagement of the weight element 50 with the link 47 or the blocks 41 may cause bending of the spring link 47 without fracturing the link. The downward and inward movement of the blocks 41 retracts the blocks from the openings 40 and draws the fingers 45 out of the slots 46.

When the means 11 has been released as just described, the string 20 is turned in a direction to disengage the latches 29 from the pins 30 and is then lowered to actuate the slips 25. The rotatable connection 10 allows the hanger H to be freely turned with respect to the liner L to effect the disengagement of the latches 29 from the pins 30. Accordingly, in situations where the liner L is held against turning by reason of the contour of the well the hanger H may be easily conditioned for actuation. When the string 20 is lowered, as described above, the cone 21 forces the slips 25 outwardly into gripping engagement with the casing C. The string 20 may then be

manipulated to free the lugs 19 from the slots 16 and the string 20 may be withdrawn from the well. As described above, the go-devil or element 50 is removed from the well, together with the string 20. Upon the disengagement of the string 20 from the hanger H the weight of the liner L is imposed on the slips 25 through the medium of the adapter 15, the packing ring assembly 24 and the cone 21. The weight transmitted through the packing ring assembly 24 compresses the assembly so that it effectively seals with the interior of the casing C. The slips 25 are adapted to dependably suspend the liner from the casing C. In the event that it becomes desirable or necessary to remove the liner L from the well a string 20 carrying an adapter 18 may be run into the well to engage the lugs 19 in the slots 16 and the string may be raised to pull the liner L and the hanger H from the well. If desired the recovery string 20 may be manipulated to re-engage the latches 29 with the pins 30 before withdrawing the hanger H and the liner L from the well.

Figs. 9, 10 and 11 of the drawings illustrate a form of the invention wherein a liner L' is supported from its lower end in a well casing C'. The embodiment of our invention illustrated in Figs. 9, 10 and 11 may be said to comprise, generally, the liner L', a support or hanger H' for supporting the liner L' in the casing C', a rotatable connection 56 between the liner L' and the hanger H', a tool T releasably engaged in the hanger H' for lowering the liner L' and the hanger H' into the well and means 57 holding the liner L' and the hanger H' against relative turning releasable to permit turning of the hanger relative to the liner to condition the hanger for actuation.

The liner L' is an elongate tubular perforate member or assembly intended for installation in the casing C'. The upper end of the liner L' is preferably provided with a head or guide 58 for centralizing the liner in the casing C'. A collar 59 is threaded on the lower end of the liner L' and carries a lower section 60. The lower liner section 60 is a tubular member and is preferably larger in internal diameter than the liner proper L'.

The hanger H' is adapted to support the liner L' in the well casing C'. In accordance with the invention the hanger H' is designed to be applied to the lower end of the liner L'. In the construction illustrated the hanger H' includes an elongate tubular body 61. The upper portion of the hanger body 61 is rotatably received in the lower liner section 60. A cone 62 is welded or otherwise secured to the hanger body 61 below the liner section 60 and a set of slips 63 is engaged on the cone 62. The outer sides of the slips 63 are toothed to effectively grip the interior of the casing C'. A suitable guide head 64 may be provided on the lower end of the hanger body 61.

The hanger H' further includes a control for the slips 63. This control includes vertically spaced rings 65 shiftable on the hanger body 61 and positioned between the cone 62 and the head 64. Outwardly bowed leaf springs 66 extend between and are secured to the rings 65. The springs 66 are adapted to frictionally engage the interior of the casing C' to resist movement of the rings 65 in the casing. Spring reins 67 connect the lower ends of the slips 63 with the upper ring 65 so that the engagement of the springs 66 with the casing C' may resist movement of the slips 63 when the cone 62 moves vertically to actuate the slips. Hook-like latches 68 depend from the upper ring 65 and releasably co-

operate with pins 69 on the body 61. The engagement of the latches 68 with the pins 69 holds the slips 63 in their down or retracted positions clear of the casing C'. The pins 69 are adapted to be released from the latches 68 by a turning movement of the hanger body 61 followed by a vertical movement of the body.

The rotatable connection 56 serves to connect the liner L' with the body 61 of the hanger H' so that the body 61 may be turned independently of the liner L' to effect the release of the pins 69 from the latches 68. The rotatable connection 56 is preferably in the nature of an anti-friction bearing means. In the construction illustrated vertically spaced sets of registering annular ball races 70 are provided in the exterior of the hanger body 61 and the interior of the lower liner section 60. Series of balls 71 are arranged in the registering races 70. The balls 71 connect the hanger body 61 and the liner L' for free relative turning and operate to connect the hanger H' and the liner L' against relative longitudinal movement and separation.

The tool T is employed to lower the assembly 25 of the liner L' and the hanger H' into the well and to manipulate the hanger H' to release and actuate the same. The tool T is in the nature of a releasable grappling tool, for example, it may be a releasable spear. In the case illustrated in 30 the drawings the tool T includes a mandrel 72 secured to the lower end of a tubular setting string 73. The mandrel 72 is tubular, having a central longitudinal opening 74. The lower portion of the mandrel 72 is tapered and of increased 35 diameter, being in the form of a wedge 75. A sleeve 76 is shiftable on the mandrel 72 and carries slips 77 engaged about the wedge 75. The slips 77 are integral parts of the sleeve 76 and tend to spring inwardly against the wedge 75 40 through their resiliency. Outwardly bowed leaf springs 78 are secured to the sleeve 76 and are adapted to frictionally engage in the hanger body 61. A latch control is provided for the slips 77 of the tool T. A pin 79 is fixed to the mandrel 72 and shifts in one of the slots 80 occurring 45 between the spaced slips 77. A lateral groove 81 is provided in the inner side of one of the slips 77 and is adapted to receive the pin 79. When the pin 79 is in the lateral groove 81 the slips 77 are retained in their retracted positions. When the pin 79 is in the upper portion of the slot 80, as illustrated in Figs. 10 and 11, the wedge 50 75 actuates the slips 77 outwardly into effective gripping and supporting engagement with the interior of the hanger body 61. The tool T is preferably engaged in the upper portion of the hanger body 61, as illustrated in the drawings. The gripping teeth 82 of the slips 77 are cut both 55 vertically and horizontally so that the tool T is operable to transmit turning movement to the hanger body 61 as well as longitudinal movement.

The means 57 is provided to prevent relative turning between the liner L' and the hanger H' 60 when the liner is being run into the well and positioned. The means 57 is releasable to allow turning of the hanger body 61 relative to the liner L' to effect the release of the pins 69 from the latches 68 so that the slips 63 may be set to support the liner L'. In accordance with the invention the means 57 may be similar to the means 11 described above, and may comprise pairs of registering openings 83 and 84 in the walls of the hanger body 61 and the lower liner section 60, respectively. In practice the open-

ings 83 and 84 are spaced below the lowermost pair of ball races 70 of the means 56. Shiftable blocks 85 are arranged in the registering openings 83 and 84 and are connected by a spring link 86. The link 86 serves to hold the blocks 85 in positions where they extend completely through the openings 83 and into the openings 84 to dependably prevent turning of the body hanger 61 relative to the liner section 60.

The means 57 is releasable by a go-devil or weight element 87 dropped through the setting string 73. The element 87 is adapted to pass down through the opening 74 in the mandrel 72 to have its lower end strike the block 85 or the link 86. The weight element 87 is adapted to flex the link 86 and to move the blocks 85 downwardly and inwardly to positions such as illustrated in Fig. 11 where they are clear of the openings 84 in the liner section 60. Pins 87a carried by the hanger body 61 may pass through slots in the blocks 85 to prevent the loss or detachment of the blocks.

It is believed that the operation of the equipment illustrated in Figs. 9, 10 and 11 will be readily understood from the foregoing detailed description. The tool T is adapted to be inserted in the hanger body 61 and actuated to grip the body so that the assembly of the hanger H' and the liner L' may be run into the well on the setting string 73. The pins 69 are initially engaged in the latches 68 to hold the slips 63 retracted and the blocks 85 engage in the openings 83 and 84 to prevent relative turning between the liner L' and the hanger body 61 so that the pins 69 cannot become disengaged from the latches 68. Accordingly, there is no danger of the slips 63 being unintentionally actuated when the tool or assembly is being run into the well. When the liner L' is in the selected position the go-devil or weight element 87 is dropped through the string 73. The lower end of the element 87 strikes the blocks 85 or the link 86, or both, to retract the blocks 85 from the openings 84. The string 73 may then be turned to turn the hanger body 61 and release the pins 69 from the latches 68. The springs 66 serve to hold the latches 68 against turning at this time. It is to be observed that the hanger body 61 may be freely turned relative to the liner L' by means of the string 73 and the tool T. Accordingly, the non-rotatable engagement of the liner L' in a crooked hole or crooked casing C' does not interfere with the release of the latch pins 69. Upon the release of the latch pins 69 from the latches 68 the string 73 is moved downwardly or allowed to settle so that the cone 62 expands the slips 63 outwardly into gripping engagement with the casing C'. The string 73 is then lowered and turned to permit retraction of the slips 77 and to latch the slips 77 retracted, whereupon the string 73 and the tool T may be withdrawn from the well. The go-devil or element 87 is withdrawn from the well together with the tool T. The slips 63 set as described above dependably support the hanger H' and the liner L' in the casing C.

Having described only typical preferred forms and applications of our invention, we do not wish to be limited or restricted to the specific details herein set forth, but wish to reserve to ourselves any variations or modifications that may appear to those skilled in the art or fall within the scope of the following claims.

Having described our invention, we claim:

1. In combination, a well liner, a hanger for supporting the liner in the well and conditioned for operation by turning movement, a tubular

setting string connected with the hanger, a rotatable connection between the liner and hanger, and means holding the hanger against turning relative to the liner releasable by an object passed through the string.

5. Means for installing a liner in a well comprising a hanger for supporting the liner in the well conditioned for operation by turning movement, a swivel connection between the hanger and liner allowing such turning movement of the hanger, an object to be dropped into the well, and means preventing relative turning between the liner and hanger releasable by said object to allow conditioning and actuation of the hanger.

10. 3. Means for installing a liner in a well comprising a hanger for supporting the liner in the well conditioned for operation by turning movement, a swivel connection between the hanger and liner allowing such turning movement of the hanger, a tubular string connected with the hanger for lowering the hanger and liner into the well, an object to be passed down through the string, and releasable means preventing turning of the hanger relative to the liner releasable by 15 said object to allow conditioning and actuation of the hanger.

20. 4. Means for installing a liner in a well comprising a hanger for supporting the liner in the well conditioned for operation by turning movement, a swivel connection between the hanger and liner allowing such turning movement of the hanger, an object to be dropped into the well, and means preventing relative turning between the liner and hanger releasable by said object to 25 allow conditioning and actuation of the hanger, the last named means including surfaces on the liner and hanger, and a member engaging said surfaces and movable by said object to a position free of one of said surfaces.

25. 5. Means for installing a liner in a well comprising a hanger for supporting the liner in the well conditioned for operation by turning movement, a swivel connection between the hanger and liner allowing such turning movement of the hanger, an object to be dropped into the well, and means preventing relative turning between the liner and hanger releasable by said object to allow conditioning and actuation of the hanger, the last named means including walls on 30 the liner and hanger defining registering openings, and a shiftable member engaged in said openings and movable by said object to a position free from at least one of said openings.

35. 6. Means for installing a liner in a well comprising a hanger for supporting the liner in the well conditioned for operation by turning movement, a swivel connection between the hanger and liner allowing such turning movement of the hanger, a tubular string connected with the hanger for lowering the hanger and liner into the well, an object to be passed down through the string, and releasable means preventing turning of the hanger relative to the liner releasable by said object to allow conditioning and 40 actuation of the hanger, the last named means including walls on the liner and hanger defining sets of registering openings, shiftable blocks in the opening, and a link connecting the blocks, the assembly of the blocks and link being in the path of the object whereby the object moves the blocks to positions where the hanger may be turned relative to the liner.

45. 7. In combination, a well liner, a hanger for supporting the liner in the well and conditioned for operation by turning movement, the liner and

5. hanger having telescopically related parts, means associated with said parts connecting the liner and hanger for relative turning, a tubular setting string releasably connected with the liner, said parts having openings, a shiftable member in said openings holding the hanger against turning relative to the liner, and an object adapted to be dropped through the string to move the member to a position clear of one of the openings to allow turning of the hanger 10 relative to the liner to condition the hanger for operation.

8. In combination, a well liner, a hanger for supporting the liner in the well and conditioned for operation by turning movement, the liner 15 and hanger having telescopically related parts, means associated with said parts connecting the liner and hanger for relative turning, a tubular setting string releasably connected with the liner, said parts having opposite sets of registering 20 openings, blocks in the sets of openings, a flexible link connecting the blocks and extending across the interior of the innermost part, and an object to be run through the string to engage the assembly of the blocks and link to withdraw 25 the blocks from openings in one of the said parts.

9. Means for installing a liner in a well comprising a hanger for supporting the liner in the well conditioned for operation by turning movement, a swivel connection between the hanger and the upper end of the liner allowing such turning of the hanger, parts on the liner and hanger having openings, and releasable means preventing turning of the hanger relative to 30 the body comprising a member engaged in said openings and adapted to be released by an object run into the well.

10. Means for installing a liner in a well comprising a hanger for supporting the liner in the well conditioned for operation by turning movement, a swivel connection between the hanger and the lower end of the liner allowing such turning of the hanger relative to the liner, the hanger and liner having telescopically related 40 tubular parts provided with aligned transverse openings, a tubular setting string extending through the liner and releasably connected with the hanger, a shiftable member extending into the openings to hold the hanger against turning relative to the body, and an element to be dropped through the string to shift the member to a position free of the opening in one of said parts to free the hanger from turning.

11. Apparatus for supporting a liner in a well 45 comprising a hanger body, a swivel connection between the body and liner, slip means carried by the body operable to grip the wall of the well to support the liner, latch means holding the slip means retracted and releasable by turning of the body, and spring held means holding the body against turning relative to the body and releasable by an object run into the well.

12. Apparatus for supporting a liner in a well comprising a hanger body, a swivel connection 50 between the body and liner, slip means carried by the body operable to grip the wall of the well to support the liner, latch means holding the slip means retracted and releasable by turning of the body, parts on the body extending one around the other and having openings, releasable means engaged in the openings and holding the body against turning relative to the liner, a tubular setting string releasably connected with the body, and a weight element to 55

70. 75.

be dropped through the string and engageable with the releasable means to release the same.

13. Apparatus for supporting a liner in a well comprising a hanger body, a swivel connection between the body and liner, slip means carried by the body operable to grip the wall of the well to support the liner, latch means holding the slip means retracted and releasable by turning of the body, parts on the body extending

one around the other and having openings, releasable means engaged in the openings and holding the body against turning relative to the liner, a tubular setting string, a grappling tool on the string releasably engaged in the body, and a weight element to be dropped through the string to release the releasable means. 5
